UNITED STATES PATENT OFFICE.

FRED L. WERNER, OF SANDUSKY, OHIO.

GARMENT SUPPORTER.

1,413,696.

Specification of Letters Patent. Patented Apr. 25, 1922.

Application filed April 20, 1921. Serial No. 462,968.

To all whom it may concern:

Be it known that I, FRED L. WERNER, a citizen of the United States, residing at Sandusky, in the county of Erie and State 5 of Ohio, have invented certain new and useful Improvements in Garment Supporters, of which the following is a specification, reference being had to the accompanying drawings.

10 Considerable difficulty has been experienced in keeping men's shirts from pulling out of the trousers, particularly at the back, or the trousers slipping down, when wearing belts, and various articles have been devised for overcoming these conditions, but they have been found inefficient, impractical, as well as more or less complicated and expensive, therefore the purpose of the present invention consists in an improved garment 15 supporter between the shirt and the trousers, so that the pressure of the belt, or even the waist band of the trousers, cooperating with the supporter, will act to overcome these difficulties.

20 Another purpose is to provide a supporter, which is very simple and inexpensive in construction, and has been found to perform the act of supporting the trousers and preventing the pulling out of the shirt 25 from the trousers, in such wise as not to tear the shirt or the inner waist band lining of the trousers, and support the trousers comfortably, and hold the trousers where they are first arranged when dressing.

30 Still another purpose consists in the provision of a supporter comprising a male and female member, one fitting within the other, and constructed of some suitable pliable or flexible material and designed to fasten to 35 the shirt, there being a narrow strap or band or strip of fabric attached to the inner lining of the waist band of the trousers, to engage over the female member, when the belt is drawn tight about the trousers, 40 thereby holding and supporting the trousers in proper position.

45 While the design and construction at present illustrated and set forth is deemed preferable, it is obvious that as a result of 50 a reduction of the invention to a more practical form for commercial purposes, the invention may be susceptible of changes, and the right to these changes is claimed, provided they are comprehended within the 55 scope of what is claimed.

The invention comprises further features

and combination of parts as will be herein-after set forth, shown in the drawings and claimed.

In the drawings:—

60 Figure 1 is a view showing the application of the improved garment supporter constructed in accordance with the invention.

Figure 2 is a sectional view on line 2—2 of Figure 1, showing how the supporter is 65 connected to the shirt, and how a portion of the supporter engages under the strap of the trousers.

Figure 3 is a perspective view of the male and female member of the garment 70 supporter as applied to the shirt.

Figure 4 is a detail perspective view of a portion of the trousers showing the strip or strap as applied to the inner lining of the 75 waist band.

Figure 5 is a detail perspective view of the male member of the supporter.

Figure 6 is a sectional view through the female member of the supporter.

Figure 7 is a view of a portion of a pair 80 of trousers and a portion of a shirt extending thereinto, with a portion of the trousers cut away showing the male fastener in dotted lines behind the shirt, the female fastener in section, with the supporting strip 85 engaged between the shirt and the female fastener.

Referring to the drawings, 1 designates a portion of a shirt or other garment and 2 designates a portion of a garment to be supported, preferably a pair of trousers, and 3 and 4 designate the male and female members of the supporter.

The male member is substantially in the 90 form of a button, comprising a base 5, which is of a relatively large diameter, and extending from one face of the base is a contracted shank 6 terminating in a head 7, which is of a diameter relatively less than the diameter of the base 5. The female member is in the 95 form of a ring, considerably larger in diameter than the base 5 of the male member, and is relatively thick, and has an opening 9 of a diameter relatively less than the diameter of the head, it being necessary to stretch 100 the ring, to make the opening telescope or fit over the head of the shank, particularly when the shirt is stretched over the head of the male member.

In order to fasten the supporter to the 110 shirt, the male member is disposed on one side of the shirt, the head of the shank is

engaged with the shirt, the shirt material is held about the shank, then the head of the shank with the shirt material over the same is forced through the opening of the ring, thereby holding the trousers from slipping and preventing the shirt from pulling out of the trousers. The ring is placed on the exterior of the shirt, while the male member is placed on the interior of the shirt. A short fabric strap or band 10 is stitched or otherwise fastened to the lining of the waist band of the trousers, and is designed to engage with the ring disposed on the exterior of the shirt, and though a usual belt is employed for tightening the waist band of the trousers, at a point above the ring of a supporter, the belt may be eliminated and the waist band of the trousers drawn tight, thereby allowing the trousers to be supported so as not to slip down as to prevent the shirt from pulling out. However the belt is preferably used in order to insure holding the trousers sufficiently up over the edges of the ring. The strap on the inner face of the trousers is designed to engage the ring of the supporter, hence insuring supporting the trousers. The male and female members of the garment supporter may be constructed of any suitable pliable or yieldable material preferably rubber, so that the ring may be stretched over the head of the shank of the button, when placed under the shirt, and also to prevent tearing of the shirt or the inner surface of the trousers.

It is to be understood that the tape or strip 10 may be placed at any suitable location on the inside of the trousers. It may be

located at a point below where the belt 2^a is worn, or it may be located at a point whereby the belt 2^a may extend over it, and over the supporter. In Figure 2 the tape or strip 10 is shown as being located on the trousers at a point below the belt 2^a, while in Figure 7 the tape or strip is disposed so that the button may slip in place directly inside of the belt line, in other words so that the belt will engage directly over the fastener and over the tape, to insure supporting the trousers and holding the shirt down.

The tape and the fastener or support may be located so as to be worn directly over the hip bone, or in front of the same, as may be found best suited to the wearer.

The invention having been set forth, what is claimed as being useful is:

1. In combination a strap secured to the inner surface of a waist band of a garment to be supported, a headed member of pliable material, and an apertured member adapted to engage over the headed member and under the strap.

2. In a garment supporter in combination a strap secured to the inner surface of the waist band of the garment to be supported, a male member having a pliable head and a reduced neck, and a flexible female member having an aperture smaller than the head and adapted to receive said head, said female member adapted to be engaged under the strap.

In testimony whereof I hereunto affix my signature.

FRED L. WERNER.
